SLUG CASTING MACHINE

Roland Schaffert, Jamaica, N. Y., assignor to
 Mergenthaler Linotype Company, a corporation
 of New York

Application August 7, 1940, Serial No. 351,693

24 Claims. (Cl. 199—47)

The invention relates to slug casting machines of the character wherein a composed line of matrices is presented to the face of a slotted mold to close the same at the front, and the mold filled with molten metal which is forced, by the action of a pump plunger, from a crucible into the mold through the crucible throat, the outlet end or mouthpiece of which is moved into contact with the rear face of the mold, so as to form a continuous path for the metal from the crucible to the mold during the slug casting operation.

The conditions which give rise to the casting of a "perfect" slug in a line casting machine are almost impossible of attainment since factors which correct or eliminate certain imperfections introduce others which are, in many cases, equally as bad. The best that can be done under the circumstances is to seek a compromise which will give, for all practical purposes, a slug as near perfection as possible. With the present improvements, slugs having practically flawless printing faces have been made, without however reducing the quality of the slug body beyond a point which would make the same unsuitable for printing. Indeed the slug bodies are good, i. e., their air content is sufficiently low to enable them to stand up under all ordinary conditions of use.

One imperfection frequently encountered in a cast slug is known as "cold face," resulting from a slow build-up of pressure on the metal in the mold as distinguished from a cold face resulting from relatively cool metal or a cold crucible mouthpiece. Where the pressure build-up is slow, the initial stream of metal flows slowly into the mold and up against the matrix line with very little impact, and by contact with the mold may become somewhat cooled before reaching the line of matrices. Under such conditions, the face of the slug has a ragged appearance, often with portions of the characters missing.

Another type of cold face is due to what may be termed "pre-cast dribbling," i. e., small amounts of metal dribbling out of the mouthpiece ahead of the main stream of metal. These small drops of metal become partially solidified in the mold and are washed up against the matrices as the main stream of metal is injected into the mold. These small prematurely solidified portions appear as cold spots here and there in the face of the slug. Pre-cast dribbling may be due to such causes as: sludgy metal being lodged in the metal pot throat near the mouthpiece and blown out ahead of the main stream;

the metal level being too high, permitting some metal to come through the mouthpiece during lockup; or a jerky or sticking plunger.

Another type of defect known as "swirls," is 5 recognized by the presence, in the faces of the characters, of small irregular areas surrounded by creases which give an uneven appearance. Swirls are caused by the sludge and oxide which float on the surface of the metal in the pot throat. In the standard pot or crucible, this sludge, which is a mixture of metal and dross, is forced out ahead of the metal during casting, and strikes the matrices first. The sludge does not cast as well as the pure metal, so that whenever it strikes, the quality of the cast is sacrificed. Furthermore, since the sludge cast is not as strong as the pure metal cast, the wear resistance of the slug face is decreased.

According to the present improvements, the 20 foregoing and other difficulties have been ob- viated by employing a special type of crucible throat structure in conjunction with a supplementary pump plunger operating mechanism which operates on the plunger through a toggle, the arrangement being such that a delayed sec- 25 ond pressure impulse is given to the plunger during the casting of the slug so as thereby to im- prove its density. The special throat structure permits a quick build-up in pressure on the 30 metal, causing it to impinge directly upon the casting faces of the matrices and thereby elim- inating the cold face due to slow pressure build- 35 up. The advantages of a quick pressure build- up have been appreciated by those skilled in the art, the result usually being obtained by provid- 40 ing a quick drop in the cam from which the pump plunger spring is controlled. Usually, however, trouble is encountered with a quick pressure build-up due to the fact that the air in the crucible throat and the mold is trapped by the metal as it rushes into the mold, thus giving a slug body which is structurally weak due to the large percentage of air contained therein.

In the improved arrangement, the crucible 45 throat, instead of continuing in an even curve directly up to the mold slot as is usually the case, is formed with a reverse bend, proceeding be- 50 yond the bend in a direction both upwardly and rearwardly, so as to present a chamber from which there branches a forwardly extending outlet passageway leading to the mouth of the crucible. The outlet passageway, while located above the bend, is a substantial distance from the upper end of the chamber, and the upper 55 end of the chamber is closed except for a nor-

mally open air escape valve. During a casting operation, the metal, due to its velocity as it traverses the bend, passes up into the chamber, thereby expelling the air through the escape valve. When the chamber is filled with metal, the escape valve closes. The closing of the valve instantaneously builds up a substantial pressure in the metal, which thereupon is forced with considerable velocity through the outlet passageway leading to the mold. As a consequence, all of the advantages of a quick build-up pressure are obtained, without the accompanying disadvantages, since the only air trapped in the slug is that which was present in the mold itself and in the outlet passageway between the mold and the chamber. This volume of air is relatively small and its effect is minimized by maintaining a relatively high pressure in the metal while the latter cools in the mold. The ability to maintain the high pressure results from the toggle arrangement, which is so designed that, despite the decreasing force exerted by the spring which operates it, the force exerted on the plunger is nevertheless increased.

The improved throat arrangement also eliminates the formation of "swirls," since, as the metal is initially forced up into the chamber, the sludge, being at the top, is carried up beyond the outlet passageway leading to the mold, with the result that the metal entering the outlet passageway, and consequently the mold, is pure type metal tapped from the main body below the sludge layer. Pre-cast dribbling is also prevented, since there will be no sludgy metal lodged in the throat to be blown out ahead of the metal stream, nor will the height of the metal in the pot make any difference during lock-up because of the reverse turn in the throat. Actually, with the improved arrangement, the metal normally does stand higher in the pot, so that there is less air to escape than would otherwise be the case.

The air escape valve preferably is adjustable to regulate the flow of escaping air, thus permitting regulation of the pressure build-up. This is desirable depending upon the type of slug being cast. The toggle spring arrangement is also adjustable so that the second or delayed impact may be properly timed.

Referring to the drawings:

Fig. 1 is a side elevation, partly in section, of a portion of a slug casting machine equipped with the present improvements, the parts being shown in their normal positions;

Fig. 2 is a similar view of a portion of the machine shown in Fig. 1, the pump plunger being shown at the commencement of its active stroke;

Fig. 3 is a view similar to Fig. 2, but with the pump plunger shown near the bottom of its active stroke;

Fig. 4 is a top plan view of the parts shown in Fig. 2;

Fig. 5 is a vertical sectional view taken on a fore-and-aft plane through the crucible throat, the parts being shown in their normal positions;

Fig. 6 is a sectional view taken on line 6—6 of Fig. 1;

Fig. 7 is a sectional view taken on line 7—7 of Fig. 5;

Fig. 8 is a vertical sectional view taken on a fore-and-aft plane through the crucible throat and illustrating the position of the parts just prior to the entry of the metal into the passageway leading to the mold; and

Fig. 9 is a view similar to Fig. 8 after the metal has entered the mold.

The improvements have been illustrated in connection with a standard slug casting machine which includes, in part, a first elevator A movable from a position wherein it receives a composed line B of matrices and spacebands to a position wherein the line is presented to the face of a slotted mold C carried by a mold disc C¹ which is rotatable to bring the mold into casting position, all as shown in Fig. 1 and as will be understood in the art. At the rear of the mold disc, there is a metal pot or crucible D containing molten metal and which may be of standard construction except as hereinafter described. The crucible D is supported in a housing D¹ equipped at the front with a pair of legs D² pivotally mounted at their lower ends on a transverse shaft (not shown) but which permits the crucible housing D¹, and consequently the crucible itself, to be rocked forwardly at the proper stage of the machine cycle to effect a lock-up between the mold and the composed line, on the one hand, and between the mold and the mouth of the crucible, on the other hand.

The pressure for the lock-up is obtained from the main cam shaft M of the machine through the medium of an edge cam M¹ mounted thereon and which rotates once during each machine cycle. The cam M¹ engages a cam follower D³ journaled in a short rearwardly extending portion of a substantially vertical lever D⁴, somewhat above the center thereof. The lever D⁴, at its upper end, is pivotally connected to a lug D⁵ projecting from the rear face of the housing D¹ and, at its lower end, is linked to another lug D⁶, projecting from the lower face of the housing D¹ at the rear thereof, the latter connection being through the medium of a rod D⁷ passing through the lever and pivotally connected to said lug. Normally, the relative locations of the crucible housing D¹ and the lever D⁴ are maintained by a spring D⁸, reacting between the lever and a collar D⁹ with which the link D⁷ is provided, the proper compression in the spring being maintained by a pair of lock nuts D¹³ threaded on the end of the link and bearing against the rear face of the lever.

In the normal position of the parts, the metal pot stands with its mouthpiece spaced from the mold, but at the proper stage of the machine cycle, a high portion of the cam M¹ engages the follower D³, thereby tilting the metal pot forward and through the spring D⁸ exerting the necessary pressure for the lock-up.

After the lock-up has been effected, the molten metal is forced into the mold by the action of a plunger E arranged for vertical reciprocation in a cylindrical chamber D¹⁰ formed in the crucible D and which communicates with the crucible mouthpiece by way of a tapered passageway D¹¹. When the plunger is in its topmost or normal position, metal enters the cylindrical chamber D¹⁰ through an aperture D¹², but during the casting of the slug, the plunger E is caused to move downwardly, thereby closing the aperture D¹² and displacing the trapped metal upwardly through the throat and into the mold.

A vertical rod E¹, connected at its lower end to the plunger E, extends upwardly through an opening formed in the cover plate of the housing D¹, above which it is pivoted at the front end of a horizontal arm E² forming part of a bell-crank lever arranged for rocking movement about a pivot rod E³ journaled in spaced vertical portions of a cantilever bracket F fixed on the machine frame (Fig. 4). The bell-crank lever is

formed also with a downwardly extending arm E⁴ provided at its lower end with a cam follower E⁵ arranged to track along an edge cam M² likewise mounted on the main cam shaft M. The arms E² and E⁴ are formed integral with a hub portion E⁶ through which the pivot rod E³ extends. The hub portion E⁶ is also formed with an arm E⁷ extending to the right (looking at the parts from the front of the machine) and beneath a long fore-and-aft arm E⁸ which likewise has a hub portion E⁹ mounted for rocking movement, on an extension of the pivot rod E³. A long powerful spring G, anchored at its lower end in the base of the machine, pulls down on the arm E⁶, at the front end of which the spring is connected, and through its engagement with the underlying arm E⁷, urges the cam follower E⁵ into engagement with the periphery of the cam M², which consequently controls the action of the pump plunger E.

The cam M² is concentric for the major portion of its circumference. However, at that phase in the machine cycle when the casting operation takes place, a depression M³ in the periphery of the cam permits the bell-crank which operates the plunger E to turn under the action of the spring G, in a direction to force the plunger downwardly (Fig. 2). The downward movement of the plunger, of course, displaces metal which passes through the passage-way D¹¹ and thence into the mold to cast the slug.

The pump plunger mechanism thus far described is substantially the same as that used in the commercial machines. It presents several disadvantages, however, which are not conducive to the formation of good slugs. For instance, when the spring G is allowed to act, it causes a quick descent of the plunger, thereby building up pressure in the trapped metal, which pressure reaches a maximum shortly after the plunger is arrested by the reaction of the metal as the mold becomes filled. The maximum pressure exerted is usually substantially higher than what it would be were the spring reacting merely between its bottom anchorage and the arm E⁸ in a position of rest as determined by the plunger in its lowermost position. In other words, the maximum pressure exerted on the metal results from impact due to the kinetic energy given up by the contracting spring, the moving parts of the pump plunger mechanism, and the molten metal which is in motion in the well and throat. After the maximum pressure has been reached, it falls off rapidly, fluctuating for a time below and above the pressure exerted by the spring when the same is in equilibrium with the plunger at the bottom of its stroke. In other words, if the pressure curve is plotted, over the period starting with the descent of the plunger until the spring reaches equilibrium at the bottom of the plunger stroke, it will be found that the curve has a damped oscillatory shape about the equilibrium pressure as an axis. The conditions are such that after the first high impact pressure is reached, the pressure falls off rapidly, reaching momentarily a pressure much below the equilibrium pressure. Indeed, under some conditions, a negative pressure momentarily exists, causing metal to be sucked out of the mold. Since, meanwhile, the cast slug is rapidly cooling, the poor structure thereof, resulting from the low pressure conditions, becomes fixed and cannot be rectified by the subsequent application of the higher equilibrium pressure.

The conditions just described are substantially eliminated, according to the present improvements, by applying a second or delayed impact pressure to the metal at or about the time the reaction to the first impact pressure becomes effective, i. e., during the period the pressure ordinarily would first drop below the equilibrium pressure. This second delayed impact prevents the pressure from falling below that which will produce an excellent slug body. Furthermore, the large pressure fluctuations are damped out more rapidly and the final equilibrium pressure is higher. The latter condition is augmented by the use of a mechanism capable of exerting an increasing pressure as the plunger descends, rather than a decreasing pressure, as is the case with the ordinary spring arrangement. This increasing pressure as the plunger descends is particularly advantageous when casting large slugs because of the greater distance the plunger descends in such cases.

The supplemental mechanism just alluded to includes a toggle device (Fig. 1) having two links H and H¹ hinged together as at H². The upper link H is fulcrumed at its center on a fixed pivot pin H³ and when it is turned in a counter-clockwise direction (looking at the parts from the left) the toggle links are straightened out, the lower link H¹ pushing down with substantial force on the bell-crank lever arm E² which, as will be recalled, is connected to the rod E¹ of the plunger (Fig. 3). The connection between the arm H¹ and the lever arm E² is designed to absorb shock and determine the period of delay between the operation of the two plunger actuating devices. It includes a rod H⁴ forming part of the link H¹ and extending slidably through a block H⁵ connected by means of a pivot pin H⁶ to the arm E² (see Fig. 6). A compression spring H⁷ encircles the rod H⁴ and reacts between the block H⁵ and a shoulder presented by the link member H¹, the normal length of the link H¹ between the pivots H² and H⁶ being determined by a nut H⁸ threaded on the end of the rod H⁴ and banking against the block H⁵. However, when the toggle is straightened out to provide the delayed supplementary pressure impact to the metal in the pot, the spring H⁷ will compress and absorb the shock occasioned thereby, the rod H⁴ merely sliding relatively to the block H⁵ (Fig. 3). The period of delay is determined by the distance between the block H⁵ and the nut H⁸ and can be varied by adjusting the position of the nut H⁸.

The force for straightening out the toggle member and for applying pressure therethrough is derived from a tension spring H⁹ anchored at the rear of the machine and connected at its front end to one arm of a shallow inverted U-shaped link H¹⁰, the other arm of which is pivotally connected to the link H at the end thereof opposite its pivotal connection with the link H¹.

When the parts are in their normal position as shown in Fig. 1, the link H is slightly off dead center in a clockwise or reverse direction as regards the pull of the spring H⁹, i. e., there is no tendency for the spring to rotate the link to straighten out the toggle. However, when the plunger descends under the influence of the main spring G, the link H is rotated in a counterclockwise direction and, after it moves through the dead center position, the spring H⁹ becomes active to continue straightening out the toggle. While the force exerted by the spring H⁹ decreases as it contracts, the nature of the toggle construc-

tion is such that the resultant force exerted on the plunger increases as the latter descends.

In order to prevent collapsing of the parts under the pull of the spring H⁹, a safety banking screw H¹¹ is provided, threaded through the U-shaped member H¹⁰ and engaging the upper edge of the link H rearwardly of its central pivot point H³.

The improved type of crucible throat structure by which a quick pressure build-up is obtained is shown in Fig. 5. Here, it will be observed, the 10 tapered passageway D¹¹, instead of leading directly up to the mouthpiece as usual, makes a reverse turn, as at J, terminating above the turn in a chamber J¹ closed at the top by a plate J². Centrally of the closing plate, is an air escape valve J³ consisting of a body portion J⁴ threaded into the chamber and which is formed at the bottom to retain a ball valve J⁵. Just above the ball, the body portion is cut away to present two opposed 15 apertures J⁶ through which air may escape from the chamber J¹ out through a passageway J⁷ communicating with the atmosphere via an aperture J⁸.

Now when the pump plunger E is depressed, metal is forced up through the tapered passageway D¹¹, around the turn J and up into the chamber J¹, the metal pushing the air before it and out through the apertures J⁶ to the atmosphere. When all the air has escaped, or in other words, when the chamber J¹ is filled with metal, the ball valve J⁵ is forced upwardly into engagement with a valve seat J⁹ located above the air outlet apertures J⁶ (Fig. 8). The closing of the ball valve prevents the escape of metal and, simultaneously with said closing, the pressure in the metal is instantaneously built up to a substantial degree.

The quick pressure build-up forces the metal out through a passageway J¹⁰ connecting the chamber J¹, just above the bend J, with the mouthpiece of the crucible, and thence into the mold (Fig. 9). Because of the quick pressure build-up, the metal enters the mold with considerable velocity, with the result that it impinges directly upon the casting faces of the matrices, thereby eliminating the cold face due to the metal flowing slowly into the mold. The principle upon which the quick pressure build-up is obtained is somewhat on the order of a hydraulic ram. It is quicker and more effective than that produced with a quick drop plunger action, and eliminates the pounding and strain on the crucible accompanying the quick drop.

It will also be apparent from Fig. 9 that the metal entering the mold is free from sludge since the latter is carried up into the chamber J¹ past the passageway J¹⁰ which communicates with the mold. In other words, the metal forming the cast slug is tapped at a point beneath the level of the sludge, consequently eliminating the formation of "swirls" which occur when the sludge is allowed to enter the mold. At this point it might be stated that the initial velocity of the metal as it traverses the bend J is sufficient to force it up into the chamber J¹. That is, the chamber is filled before the metal flows out of the passageway J¹⁰. The conditions ordinarily giving rise to pre-cast dribbling are also absent when the improved crucible throat structure is used.

Provision is also made for regulating the pressure build-up to suit the type of slug being cast. For this purpose, the valve body J⁴ is threaded at the top to receive a cap J¹¹ provided with an aperture J¹² and which can be turned from a position wherein the air passageway J⁷ is com-

pletely open to a position wherein it is completely closed.

Of course, the quicker the air is allowed to escape, the quicker the pressure build-up will be. 5 However, where the slug faces are not difficult to cast, advantage can be taken of the greater slug solidity obtainable with a slower pressure build-up.

In the accompanying drawings, the invention has been shown merely in preferred form and by way of example, but obviously many variations and modifications may be made therein which will still be comprised within its spirit. It is to be understood, therefore, that the invention is 10 not limited to any specific form or embodiment, except insofar as such limitations are specified in the appended claims.

Having thus described my invention, what I claim is:

1. In or for a slug casting machine, a pot crucible from which molten metal is pumped into a mold to form a slug and which has a throat terminating in an air chamber into which the metal passes prior to its entry into the mold, an air outlet for the chamber, and a passageway, through which the metal passes to the mold, connecting the mouth of the crucible with the chamber at a point below the air outlet thereof.

2. In or for a slug casting machine, a pot crucible from which molten metal is pumped into a mold to form a slug and which has a throat terminating in an air chamber into which the metal passes prior to its entry into the mold, said chamber being of a size to accommodate at least the layer of sludge floating on the surface of the metal in the throat, and a passageway, through which the metal passes to the mold, connecting the mouth of the crucible with the chamber at a point below the sludge layer.

3. In or for a slug casting machine, a pot crucible from which molten metal is pumped into a mold to form a slug and which has a throat terminating in an air chamber into which the metal passes prior to its entry into the mold, a passageway connecting the mouth of the crucible with the chamber, and an air relief valve for said chamber, said valve being automatically closable after the escape of air from the chamber.

4. In or for a slug casting machine, a pot crucible from which molten metal is pumped into a mold to form a slug and which has a throat terminating in an air chamber into which the metal passes prior to its entry into the mold, a passageway connecting the chamber with the mouth of the crucible, and an air relief valve adapted to be closed by the metal as it rises in the chamber, the closing of the valve acting to build up pressure in the metal to force the same through the passageway and into the mold.

5. In or for a slug casting machine, a pot crucible from which molten metal is pumped into a mold to form a slug and which has a throat terminating in an air chamber, an air relief valve for the chamber closable automatically by the rise of the metal in the chamber, and a passageway connecting the mouth of the crucible with the chamber at a point below the air outlet, the closing of said valve acting to build up pressure in the chamber to force the metal through the passageway and into the mold.

6. In or for a slug casting machine, a pot crucible from which molten metal is pumped into a mold to form a slug and which has a throat terminating in an air chamber, said

chamber being of a size to accommodate at least the layer of sludge floating on the surface of the metal in the throat, an air relief valve in the chamber closable automatically by the rise of metal in the chamber, and a passageway connecting the mouth of the crucible with the chamber at a point below the sludge layer, the closing of said valve acting to build up pressure in the chamber to force sludge-free metal through the passageway and into the mold.

7. In or for a slug casting machine, a pot crucible from which molten metal is pumped into a mold to form a slug and which has a throat with a bend communicating with an air chamber located thereabove, and a passageway connecting the mouth of the crucible with the throat at a point between the chamber and the bend.

8. In or for a slug casting machine, a pot crucible from which molten metal is pumped into a mold to form a slug and which has a throat with a reverse bend communicating with an air chamber extending upwardly and rearwardly from said bend, and a passageway connecting the mouth of the crucible with the throat at a point between the bend and the chamber.

9. In or for a slug casting machine, a pot crucible from which molten metal is pumped into a mold to form a slug and which has a throat terminating in an air chamber into which the metal passes prior to its entry into the mold, a passageway connecting the mouth of the crucible with the chamber, an air relief valve for said chamber closable automatically after the escape of air from the chamber and acting upon closing to build up pressure to force the metal through the passageway and into the mold, and adjustable means for regulating the escape of air through said valve.

10. In or for a slug casting machine, a pot crucible from which molten metal is pumped into a mold to form a slug and which has a throat formed with an upward bend terminating in an air chamber above the bend, a passageway connecting the mouth of the crucible with the throat at a point between the chamber and the bend, and an adjustable air relief valve for said chamber.

11. In or for a slug casting machine, the combination of a pot crucible from which molten metal is pumped into a mold to form a cast slug, a plunger by which the pumping action is effected, and a plurality of devices each applying independently a pressure exerting force to the plunger as the slug is being cast.

12. In or for a slug casting machine, the combination of a pot crucible from which molten metal is pumped into a mold to form a cast slug, a plunger by which the pumping action is effected, and a plurality of devices each applying independently a pressure exerting force to the plunger as the slug is being cast, said forces acting at different times.

13. In or for a slug casting machine, the combination of a pot crucible from which molten metal is pumped into a mold to form a cast slug, a plunger by which the pumping action is effected, and a plurality of devices each applying independently a pressure exerting force to the plunger as the slug is being cast, said forces being timed so that one is applied substantially at the time the reaction of the metal to the other force becomes effective.

14. In or for a slug casting machine, the

combination of a pot crucible from which molten metal is pumped into a mold to form a cast slug, a plunger by which the pumping action is effected, and means including a toggle device for applying to the plunger a pressure exerting force increasing in magnitude over the active plunger stroke.

15. In or for a slug casting machine, the combination of a pot crucible from which molten metal is pumped to form a cast slug, a plunger by which the pumping action is effected, a spring for applying a pressure exerting force to the plunger, and a device for applying a second pressure exerting force to the plunger to supplement the force applied thereto by the spring, said device acting subsequently to and independently of the spring.

16. In or for a slug casting machine, the combination of a pot crucible from which molten metal is pumped to form a cast slug, a plunger by which the pumping action is effected, a spring for applying a pressure exerting force to the plunger, a device for applying a second pressure exerting force to the plunger to supplement the force applied thereto by the spring, and means for delaying the action of said device for a predetermined period after the commencement of the plunger stroke.

17. In or for a slug casting machine, the combination of a pot crucible from which molten metal is pumped to form a cast slug, a plunger by which the pumping action is effected, a spring for applying a pressure exerting force to the plunger, a device for applying a second pressure exerting force to the plunger to supplement the force applied thereto by the spring, means for delaying the action of said device for a predetermined period after the commencement of the plunger stroke, and adjustable means for varying said period as desired.

18. In or for a slug casting machine, the combination of a pot crucible from which molten metal is pumped to form a cast slug, a plunger by which the pumping action is effected, a spring for applying a pressure exerting force to the plunger, and means including a toggle device for applying a second pressure exerting force to the plunger to supplement the force applied thereto by the spring.

19. In or for a slug casting machine, the combination of a pot crucible from which molten metal is pumped to form a cast slug, a plunger by which the pumping action is effected, a spring for applying a pressure exerting force to the plunger, and means including a toggle device connected between the plunger and a fixed part of the machine for applying a second pressure exerting force to the plunger to supplement the force applied thereto by the spring, the toggle connections being such that the force exerted by said means increases in magnitude during the active plunger stroke.

20. In or for a slug casting machine, the combination of a pot crucible from which molten metal is pumped to form a cast slug, a plunger by which the pumping action is effected, a spring for applying a pressure exerting force to the plunger, and means including a toggle device connected between the plunger and a fixed part of the machine for applying a second pressure exerting force to the plunger to supplement the force applied thereto by the spring, the toggle connections being such that no force is exerted by said means during the initial portion of the plunger stroke, whereas a force increasing in

magnitude is exerted thereby during a subsequent portion of the plunger stroke.

21. In or for a slug casting machine, the combination of a pot crucible from which molten metal is pumped to form a cast slug, a plunger by which the pumping action is effected, a spring for applying a pressure exerting force to the plunger, means including a toggle device connected between the plunger and a fixed part of the machine for applying a second pressure exerting force to the plunger to supplement the force applied thereto by the spring, the toggle connections being such that no force is exerted by said means during the initial portion of the plunger stroke, whereas a force increasing in magnitude is exerted thereby during a subsequent portion of the plunger stroke, and adjustable means for varying the extent of that portion of the plunger stroke during which no force is exerted.

22. A slug casting mechanism including, in combination, a pot crucible from which molten metal is pumped into a mold to form a slug and which is provided with a throat terminating in an air chamber, an air outlet for the chamber, a passageway through which metal passes to the mold connecting the mouthpiece of the crucible with the chamber at a point below the air outlet, means acting automatically to close the air outlet when metal pumped from the crucible fills the air chamber and thereby build up pressure to force the metal through the passageway and into the mold, a plunger for effecting the pumping action, and a plurality of devices each applying independently a pressure exerting force to the plunger, the action of one of said devices being delayed until after the mold has been filled with molten metal.

23. A slug casting mechanism including, in combination, a pot crucible from which molten

metal is pumped into a mold to form a slug and which is provided with a throat terminating in an air chamber, an air outlet for the chamber, a passageway through which metal passes to the mold connecting the mouthpiece of the crucible with the chamber at a point below the air outlet, means acting automatically to close the air outlet when metal pumped from the crucible fills the air chamber and thereby build up pressure to force the metal through the passageway and into the mold, a plunger for effecting the pumping action, a plurality of devices each applying independently a pressure exerting force to the plunger, the force exerted by one of said devices increasing in magnitude over the active plunger stroke, and means for delaying the action of said device until after the mold has been filled with metal.

24. A slug casting mechanism including, in combination, a pot crucible from which molten metal is pumped into a mold to form a slug and which is provided with a throat terminating in an air chamber, an air outlet for the chamber, a passageway through which metal passes to the mold connecting the mouthpiece of the crucible with the chamber at a point below the air outlet, means acting automatically to close the air outlet when metal pumped from the crucible fills the air chamber and thereby build up pressure to force the metal through the passageway and into the mold, a plunger for effecting the pumping action, a spring device for applying a pressure exerting force to the plunger, means including a toggle mechanism for independently applying a pressure exerting force to the plunger increasing in magnitude over the active plunger stroke, and means for delaying the action of the toggle mechanism until after the mold has been filled with metal.

ROLAND SCHAFFERT.
